UNITED STATES PATENT OFFICE.

GEORGE F. KING, OF SWAMPSCOTT, MASSACHUSETTS.

DESIGN FOR A WRITING-PEN.

SPECIFICATION forming part of Design No. 14,144, dated July 31, 1883.

Application filed April 25, 1883. Term of patent 14 years.

To all whom it may concern:

Be it known that I, GEORGE F. KING, of Swampscott, in the county of Essex and State of Massachusetts, have invented and produced 5 a new and original Design for Writing-Pens, of which the following is a full, clear, and exact description.

This improved design for writing-pens consists in having a cut or opening in each of its 10 side edges of the body portion of the pen a short distance back of the slit between its two nibs, each of which openings has two inclined or beveled edges, which at their inner and approaching ends connect with open ends of a 15 curved or circular line, all substantially as hereinafter described and shown.

In the accompanying drawing is illustrated a writing-pen of the present improved design.

A in the drawing represents in back view a 20 writing-pen. *a a* are its side edges; *b b*, its two nibs, and *c* the opening between the nibs. *d d*

are openings cut in the side edges, *a a*, of the pen, one on each side, extending inward from the edge in an inclined direction toward each other, as at *f*, and their inner ends join or connect with the ends of a curve or circular line, *g*, forming a continuation thereof, substantially as shown in the accompanying drawing.

What I claim, and desire to secure by Letters Patent, is—

The design for a writing-pen having in each 30 of its edges *a a* the inclines or bevels *f f* and opening *g*, substantially as described and shown.

In testimony whereof I have hereunto set my 35 hand in the presence of two subscribing witnesses.

GEO. F. KING.
